PICTURE FRAME

Frank D. Bogia, Clifton, N. J., assignor to Grant
Positive Corporation, New York, N. Y., a cor-
poration of New York

Application November 13, 1943, Serial No. 510,216

2 Claims. (Cl. 40—152.1)

1

This invention relates to devices for displaying pictures and the like for temporary or permanent observation.

The ordinary commercial mounts for pictorial representations of persons and things, commonly consist of a rigid frame snugly enclosing a picture, with or without a transparent protective panel, a mask and a stiff back support, all being permanently affixed to one another and requiring considerable time in assembly.

While the present invention is capable of other uses, it is primarily designed for use under conditions where time is of consequence. The present device is particularly useful at resorts where parties have small pictures taken and decide to have an enlargement made. While the enlargement can be made promptly, it likewise must be framed promptly. Accordingly, the primary object of this invention is to provide a means whereby a photograph may be readily mounted in a minimum of time.

A further object of the invention is to provide a means of mounting a photograph at a minimum of cost so that the completed ensemble may be sold at a low price.

It is a further object of the present invention to provide a picture display mount so devised that the several parts are normally held firmly in proper assembled relation, but equally capable of instant disassociation for the substitution of other subject matter.

A further feature is in the provision of non-metallic spring clamps whereby the picture, its transparent facing, mask and back plate, may be adequately held in positive juxtaposition, or released for changing the picture in a moment of time.

Another purpose is to produce a picture mount of pleasing appearance, composed of simple parts, inexpensive to manufacture, and of indefinite durability.

These objects, together with others which will later appear, are accomplished by the novel and practical construction, combination and arrangement of parts, hereinafter described and illustrated in the accompanying drawing, constituting a pictorial complement of this disclosure, and in which:

Figure 1 is an expanded perspective view showing the several parts in sequence which together constitute an embodiment of the invention.

Figure 2 is a vertical sectional view of the mount as assembled for use.

Figure 3 is a plan view of the rear plate in de-

2

tail showing the spring clips in position and the integral easel support.

Figure 4 is a fragmentary view of the same showing means to retain the clips in position.

Figure 5 is a fragmentary sectional view of the same, drawn to an enlarged scale.

Figure 6 is a detail view in perspective of the clip.

Figure 7 is a perspective view, similar to Fig. 6, but showing a modified form of clip.

The structure, as shown in the drawing, is composed of a plate 10 of transparent material, such, for instance, as clear glass or other light transmitting substance, the plate being of substantial thickness and strength, preferably—but not necessarily—rectangular in outline.

Rearward of the plate is a relatively thin mask 11, of paper or the like, its central portion being removed, as at 12, forming in effect a frame of any preferred contour, the margin of which may bear embellishments 13 of any desired character.

A display card 14 bears a picture, photograph, portrait or selected matter 15, so arranged as to be viewed through the opening in the mask 11, and is held in position thereagainst by a relatively stiff backing plate 16, such as pasteboard or similar material; all of these several elements are of uniform size, but vary in thickness.

If desired, the backing plate 16 may have cuts 17 defining a prop 18, bendable outwardly on the weakened line 19, constituting a hinge whereby the structure forms an easel.

In order to retain these elements in their proper established relation, they are held by spring clips 20, preferably made from short sections of a non-metallic tube, split lengthwise and passed over the edges of the assembled elements, at such points as may be preferred, binding the parts firmly together.

In order to avoid the possibility of casual displacement of the clips, the back plate 16 may be provided with an elongated groove 21 (see Figures 4 and 5), to receive one of the edges 22 of the clip, or, as a modification shown in Fig. 7, the rear edge of the clip may be formed with sharply defined serrations adapted to indent the material of the plate.

These clips are readily removed by raising them outwardly from the several parts, or by sliding them endwise.

It is to be noted that the clips do not obscure any material part of the structure, but present an ornamental appearance, in addition to their clamping effect and ease of application or removal.

Having thus described the invention, what is claimed as new and sought to secure by Letters Patent, is:

1. A picture frame in the form of an easel, comprising a back, a hinged cut out portion on the back to permit the same to stand upright, a picture applied to the back, a mat applied to the picture, a protective covering over the mat and means to secure the several elements together comprising split tubular spring clips to engage selected areas of the edges of the members, said back being provided on its rear surface with grooves to receive one edge of the spring clips.

2. A picture frame in the form of an easel, comprising a back, a hinged cut out portion on the back to permit the same to stand upright, a picture applied to the back, a mat applied to the picture, a protective covering over the mat and means to secure the several elements together comprising split tubular spring clips to engage selected areas of the edges of the members, said back being provided on its rear surface with grooves to receive one edge of the spring clips and one edge of the clips being provided with teeth to engage said grooves.

FRANK D. BOGLIA.
